his Attorney.

UNITED STATES PATENT OFFICE.

MICKLE CLARK, OF CHICAGO, ILLINOIS.

ELECTRICAL CONDENSER.

Application filed February 1, 1926. Serial No. 85,179.

My invention relates to improvements in electrical condensers especially adapted for use in radio receiving sets and has for its object the provision of a simple and efficient construction of this character capable of delicate tuning adjustments and also capable of economical manufacture.

Other objects will appear hereinafter.

The invention consists in the combination and arrangements of parts hereinafter described and claimed.

The invention will be best understood by reference to the accompanying drawings forming a part of this specification, and in which,

Fig. 1 is a partial plan view of a condenser embodying the invention;

Fig. 2 a section taken on line 2—2 of Fig. 1; and

Fig. 3 a section taken on line 3—3 of Fig. 1.

The preferred form of construction as illustrated in the drawings comprises two sheets 4 and 5 of suitable metal arranged parallel to and a short distance from each other, the sheet 5 being provided with an inwardly offset edge portion 6 secured to the sheet 4 by means of rivets 7. Both sheets are secured by screws 8 to a suitable support or post 9 as indicated. A suitable binding post 10 is mounted on the secured edges of said sheets to facilitate electrical connection therewith.

A plurality of internal plates 11 made of suitable metal are interposed between the sheets 4 and 5 as shown. The plates 11 are mounted between sets of tangs 12 struck up from the sheet 5 and provided with insulating blocks 13 whereby said plates 11 are permanently attached to but insulated from the sheet 5. Each plate 11 is provided with a laterally extending arm or finger 14 upon which is mounted a suitable binding post 15 for effecting electrical connection therewith. Adjusting screws 16 are provided for each of the plates 11, said adjusting screws being threaded in the plate 4 passing freely through an enlarged opening 17 in the corresponding plate 11 and resting against the plate 5 as shown and whereby the distance between the plates 11 and the sheet 4 may be slightly adjusted as desired.

By this arrangement a simple and effective condenser, or plurality of condensers, is provided in which said condensers may be nicely adjusted or tuned into unison with

each other or other condensers. The specific form and arrangement of parts constitutes a simple, effective and economical one for the purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A condenser comprising two external plates; an internal plate interposed between said external plate, said internal plate being attached to, carried by but insulated from one of said external plates and free from said other external plate and means for adjusting said external plates laterally toward and away from each other thereby adjusting the distance between said internal plate and said other external plate, substantially as described.

2. A condenser comprising two external plates attached to each other at one edge and arranged substantially parallel to each other a short distance apart; an internal plate permanently attached to but insulated from one of said external plates; a binding post attached to said external plates; a separate binding post for said internal plate; and means for adjusting the distance between said external plates, substantially as described.

3. A condenser comprising two external plates electrically connected together at one edge and arranged substantially parallel to each other a short distance apart; a plurality of internal plates permanently attached to but insulated from one of said external plates; a binding post attached to said external plates; a separate binding post for each of said internal plates; and means for adjusting the distance between said internal plates and said other external plate, substantially as described.

4. A condenser comprising two external plates electrically connected together at one edge and arranged substantially parallel to each other a short distance apart; a plurality of internal plates permanently attached

to but insulated from one of said external plates; a binding post attached to said external plates; a separate binding post for each of said internal plates; and an adjusting screw passing freely through each of said internal plates and connected with said external plates, substantially as described.

5. A condenser comprising two sheets of metal arranged substantially parallel to each other a short distance apart, one of the edges of said sheets being brought and secured together; a binding post on said secured edges;

a plurality of sets of tangs struck up from one of said sheets to constitute plate mountings; insulating blocks on said tangs; plates 15 mounted in said blocks between said sheets; an individual binding post on each of said plates; and an adjusting screw passing freely through each of said plates and connected with said sheets, substantially as de- 20 scribed.

In testimony whereof I have signed my name to this specification.

MICKLE CLARK.
